FEEDING MECHANISM FOR NIPPLE
THREADING MACHINES AND THE
LIKE

George B. Marsden, Chicago, Ill., assignor to Chicago Nipple Manufacturing Company, Chicago, Ill., a corporation of Delaware

Application May 27, 1949, Serial No. 95,636

5 Claims. (Cl. 10—91)

1 This invention relates to feeding mechanism for nipple threading machines and the like and more particularly to a mechanism for automatically chucking nipples and feeding them to the chasers.

Heretofore nipples have been placed in the chucks by hand and the chucks have been moved toward the chasers either manually or under direct manual control. After threading one end of a nipple it has been reversed by hand for a second threading operation to thread its opposite end. This is a very laborious and tiring procedure and is relatively slow.

It is one of the objects of the present invention to provide a feeding mechanism by means of which manual effort is minimized and which is adaptable to full automatic operation completely eliminating manual effort.

Another object is to provide a feeding mechanism in which the nipples are automatically fed from one chuck to another and in which the chucks are so related that the nipple is reversed so that both ends are threaded. For handling relatively short or close nipples the invention provides a transfer mechanism to transfer the nipples from one chuck to the other and to position them in the chucks with the proper length projecting from the chuck to be threaded.

Still another object is to provide a feeding mechanism in which the chucks are moved from a loading to a cutting position and movement of the chucks operates the clamping jaws therein. According to one feature of the invention, supplemental gripping jaws are provided to hold the nipples in the chucks during initial movement of the chucks.

A further object is to provide a feeding mechanism in which the chuck jaws are spring loaded to enable them to handle nipples of varying outside diameters. In addition, the springs which load the chuck jaws serve the function of helping to absorb the inertia of the chucks thereby minimizing shock.

A still further object is to provide a feeding mechanism which can accommodate nipples of varying lengths from the maximum nipple length down to and including extremely short or close nipples and which can handle nipples having a substantial range of external diameters with a minimum of set up and adjustment time.

The above and other objects and advantages of the invention will be more readily apparent when read in connection with the accompanying drawings, in which—

Figure 1 is a plan view of a feeding mechanism 55

2 embodying the invention showing the parts in loading position and with the transfer mechanism omitted;

Figure 2 is a view similar to Figure 1 showing the parts in cutting position;

Figure 3 is a side elevation showing the parts in loading position;

Figure 4 is a view similar to Figure 3 showing the parts in cutting position;

Figure 5 is an enlarged end view of the chucks with one of the chucks in central section;

Figure 6 is an end view of a chuck illustrating the supplemental gripping jaws;

Figure 7 is a partial perspective view illustrating the cam release mechanism for the supplemental jaws;

Figure 8 is a partial sectional view showing the guide means for the chucks;

Figure 9 is a partial end view showing the chucks in loading position and illustrating the transfer mechanism; and

Figure 10 is a view similar to Figure 9 showing the parts in feeding position.

The mechanism as illustrated is applied to a standard nipple threading machine having a base or bed plate 10 with a pair of standard chasers 11 rotatably mounted on one end of the bed plate. The chaser may be driven by a motor or any other desirable type of drive mechanism indicated at 12 and may contain the usual thread cutters and the usual chamfering tool for chamfering the ends of the nipples. Each of the chasers is of the type in which the threading heads are released by pressure against the chamfering tool when the thread on the nipples is completed. A resetting lever 13 is pivoted on the outside of the chasers and will rock clockwise from the position shown in Figures 3 and 4 when the threading tools are released. In addition to releasing the threading tools by the operation of the chamfering tool, the chasers may be opened by turning the levers 13 clockwise from the position shown in Figures 3 and 4.

The table or bed 10 is provided with ways 14 as best seen in Figure 5 on which a pair of carriages 15 are slidably supported. The carriages 15 are identical except that they are reversed with respect to each other. Each carriage has an upwardly extending frame 16 so that it is U-shaped as seen from the end of the machine. A chuck 17 is rotatably supported in each of the carriages for pivotal movement about a vertical axis. The chucks during operation of the machine are adapted to turn from the position shown in Figure 1 in which the chucks are

in horizontal alignment to the position of Figure 2 in which the chucks are parallel to each other and are aligned respectively with the chasers 11.

The internal construction of one of the chucks is illustrated in Figure 5. From this figure it will be seen that the chuck comprises a main body 18 having a conically tapered cavity in its outer end to receive a series of gripping jaws 19. The jaws are connected to a tube 21 which extends out of the chuck body and through which the jaws may be pulled into the body so that they will be cammed inward by the tapered recess to grip a nipple or other work piece. The tube has an internal diameter slightly in excess of the maximum diameter of a work piece to be handled by the machine so that the work pieces can pass straight through the chucks from one end to the other thereof.

The two carriages 15 are connected by a bracket 22 which is connected through a spring 23 to the piston of a fluid motor or air cylinder 24. When air is supplied to the rear end of the cylinder 24, the piston will move the carriages simultaneously toward the chasers to feed the nipples into the chasers, and when the air is supplied to the forward end of the cylinder 24, the carriages will be retracted. To turn the chucks on the carriages during movement thereof, a cam plate 25 is mounted on the bed 10 and may be adjusted longitudinally by screws 26. The cam plate is formed with a pair of similar cam tracks 27 extending generally longitudinally thereof and which receive cam rollers 28 formed on levers 29 which are rotatably mounted on the carriages. The cam tracks 27 are so shaped as illustrated that when the carriages are retracted to their feeding position as shown in Figure 1 the levers 29 are substantially in alignment and when the carriages are advanced to their cutting position the levers will be rocked, as shown in Figure 2. Each of the levers is formed with a gear segment meshing with a similar gear segment 31 carried by the adjacent chuck so that during movement of the carriages the chucks will be turned through 90°. By proper adjustment of the cam plate 25 alignment of the chucks in the feeding position can be assured and proper turning thereof to the cutting position can also be obtained accurately.

During turning movement of the chucks from the feeding to the cutting position the tubes 21 in the chucks are pulled away from the chucks to cause the jaws to grip a work piece. For this purpose each of the carriages carries a pair of cam members 32 pivoted at 33 on the carriages, there being an upper and lower cam member on each carriage, as best seen in Figures 3 and 4. The cam members 32 are formed with cam slots 34 which are curved about the pivotal centers of the respective chucks throughout approximately the first 30° of their lengths from the pivoted ends of the cam members. The remaining portions of the slots toward the free ends of the cam members are curved on an increasing radius so that during the final 60° the cam slots lie beyond a circle which is a continuation of the initial part of the cam tracks. The cam tracks receive rollers 35 which are carried by the tubes 21 as best seen in Figure 5 so that as the chucks turn from the position of Figure 1 to the position of Figure 2 the rollers 35 will travel throughout the length of the cam slots 34. During initial turning of the chucks from the position of Figure 1 to that of Figure 2 the rollers will move

through the circular portions of the tracks and will not affect the chucks. However, during the final 60° of movement the tubes 21 will be placed under tension to draw the gripping jaws into the chuck jaws so that they will be cammed into engaged position.

In order that the chucks may accommodate nipples of varying diameter, the cam members 32 are allowed to pivot about their mountings 33 so that the tubes 21 will not always be cammed to the same position as the chucks turn. The cam members are normally held in a predetermined position by heavy compression spring units 36 which are carried by the carriages and which have thrust rods 37 extending therefrom and are normally urged outward thereof by the springs. The rods 37 are connected through levers 38 to the cam members 32 and normally urge the cam members against stops 39 which determine the limit of travel of the cam members in one direction. In the event a nipple or work piece slightly over size is placed in the chuck, the cam members can move against the force of the spring units to insure a tight grip of the work piece without damage to any of the parts.

When the chucks start to turn from their loading to their cutting position as the carriages move forward, the chucks and the carriages develop a considerable amount of inertia which might damage the cam guiding mechanism and force the nipples against the threading dies with a considerable shock. It will be noted, however, that with the spring construction as shown a substantial part of this inertia will be absorbed by the springs so that damage to the parts is prevented and the carriages will move into the chasers at the proper speed. Thus the inertia of the parts can be utilized to assist in compressing the springs and to insure that the nipples or work pieces will be tightly gripped in the chucks. In order further to reduce the speed of movement of the carriages as they approach the chasers, a cam 41 is connected to the carriages to move therewith and will engage a valve 42 when the carriages reach a position adjacent the chasers. The valve 42 is connected through a conduit 42a to the forward end of the cylinder 24 to close the vent therefrom or to supply air thereto to cushion the force of the piston so that the nipples will be presented smoothly and with a relatively low degree of force to the chasers. During the initial movement the spring 23 is compressed and after the valve 42 is opened so that the piston tends to stop this spring will expand to insure that the nipples will be fed into the chasers at least to the point where the chasers themselves have cut a sufficient length of thread on the nipples to draw them into the chasers.

It may be noted that particularly in the threading of galvanized nipples an extremely heavy grip by the chucks is required to insure proper holding of the nipples during the thread cutting. In the construction shown two spring units 36 are employed for each of the chucks and these units may have a compression force of approximately one thousand pounds per inch and are preferably preloaded to approximately seventy-five per cent (75%) of that amount. The levers 38 and the effective angle of the cam tracks 34 are such as to provide an overall mechanical advantage on the order of 18:1 between the chuck jaws and the springs so that a very heavy grip is provided on the nipples. At the same time a relatively small air cylinder operating on an air pressure on the order of 60 to 70

pounds may be employed so that the mechanism does not have extremely high power requirements and is still capable of developing the necessary high gripping forces.

In order to insure proper alignment of the chucks when they are in their feeding position in spite of the fact that there may be a slight amount of play or looseness between the cam tracks 27 and the chucks, there is preferably provided a small permanent magnet 43 on each of the carriages to cooperate with a keeper 44 on the chucks. The magnet and keeper are so placed that when the chucks are in the feeding position they will be in contact and the magnetic force will tend to hold them in contact so that the chucks will be accurately aligned without interfering with turning of the chucks during forward movement of the carriages. To insure that the chucks will be properly aligned with the chasers during threading, each of the chucks carries a tubular sleeve 45 which receives a guide pin 46 fixedly carried by the bed 10. The guide pin and sleeve are relatively short so that the pin will enter the sleeve only during the final part of the movement of the carriages toward the chasers, and during this final movement will accurately align the chucks with the chasers so that the nipples will be properly centered in the chasers. The guide sleeve and pin may be constructed as best seen in Figure 8, the sleeve having a cylindrical bore 47 therein and being recessed at its forward end to receive a hardened ring 48 which may be held in place by a retainer ring 49 screwed on to the front end of the sleeve. The pin 46 is cylindrical and of substantially the same diameter as the ring 48 throughout most of its length but is tapered as indicated at 51 at its forward end to enter the ring 48 even though the parts are slightly out of alignment. With this construction even though there should be a small amount of play in the cam mechanism which turns the chucks, accurate alignment of the nipples with the chasers is insured during the actual threading operation.

In order to prevent the nipples from being thrown out of the chucks during initial turning of the chucks and prior to gripping of the nipples by their gripping jaws, auxiliary friction gripping jaws are provided to hold the nipples in place. As seen in Figures 5 to 7, these auxiliary jaws overlie the front ends of the chucks and are formed by levers 52 pivoted to the chucks at 53 and having their lower ends shaped to provide friction gripping jaws 54 in alignment with the chuck openings. The pivot pins 53 support a yoke member 55 having an up-standing extension 56 forming a guide. Links 57 are pivoted to the upper ends of the levers and are yoked at their upper ends to be guided by the extension 56, the upper ends of the levers 57 being connected by pivot pins 58. A spring 59 is connected to one of the pivot pins 58 and to an anchor pin 61 on the yoke 55 to urge the pivot pin 58 downward thereby to spread the upper ends of the levers 52 and to urge the jaws 54 thereon together. The jaws are of such a size that they will grip a nipple frictionally to hold the nipple from being accidentally thrown out of the chuck during initial turning thereof but with insufficient force to prevent a nipple from being inserted in the chuck.

In threading long nipples the auxiliary gripping jaws may be effective at all times since the nipples can be forced therefrom. However, for threading short nipples it is necessary to re-

lease the auxiliary gripping jaws associated with the chuck which holds the nipple during threading of its second end in order that the complete nipple can be removed. For this purpose a cam device as shown in Figures 5 and 7 is provided and consists of a cam plate 62 fixedly secured to the carriage frame 16. The plate 62 carries a pivot cam lever 63 having a cam end 64 thereon and which is urged outwardly of the plate by a spring 65. The cam end 64 is so positioned that it will engage one of the pivot pins 58 as the chuck turns in the frame. When the carriages are moving forward the pin 58 will engage the right end of the cam end 64 as seen in Figure 7 and will swing the cam lever 63 inward against the spring 65 without affecting the supplemental gripping jaws 54. However, on returning movement the pin 58 will ride up over the cam end 64 to raise the upper ends of the levers 52 thereby pulling the upper ends of levers 52 inward and opening the jaws 54.

For threading relatively long nipples, the nipple blank is inserted from one side of the machine as, for example, the lower side as seen in Figure 1 into the lower chuck. At this time the supplemental jaws will yield to permit insertion of the nipple. The blank is pressed forward so that its end extends from the chuck a sufficient distance for threading, suitable stops being provided for this purpose. With the nipple in the chuck, air may be supplied to the rear end of the cylinder 24 to move the carriages forward toward the chasers. During this movement, as described above, the chuck jaws will be caused to grip the nipple tightly, and the nipple will be fed into the chaser to be threaded. Upon completion of the threading operation, the chaser will trip and will open to release the nipple so that it can be pulled out of the chaser. At this time the levers 13 on the chasers will rock clockwise, as seen in Figures 3 and 4, and this movement of the levers may be utilized to control a valve 42b to admit air through a conduit 42c to the forward end of the cylinder 24. The carriages will then be retracted by the cylinder to the loading position, and the jaws of the chucks will be opened to release the nipple.

During the retracting motion of the carriages the chasers are reset for a subsequent threading operation by returning the levers 13 to the position shown in Figures 3 and 4. For this purpose each of the carriages carries a threaded rod 66 extending through an opening in the adjacent lever 13. Each of the rods 66 carries stop nuts 67 adjacent its outer end which will engage the lever 13 when the carriages are retracted to rock it back to its normal position with the cutters closed to be ready to thread the next nipple. The rods 66 may also carry additional stop nuts 68 adjacent the carriages which will engage the levers 13 at the end of a threading operation to open the chasers in the event the normal tripping mechanism should fail.

With the carriages in their loading position at the completion of the first threading operation, a new nipple blank may be forced into the lower chuck. This will force the original blank from the lower chuck into the upper chuck with its unthreaded end extending inward and with the new blank having its end projecting from the lower chuck. At this time air may be admitted again to the rearward end of the cylinder 24 to move the carriages forward. It will be noted that the lower chuck turns counterclockwise and the upper chuck turns clockwise.

so that the unthreaded end of the first blank will be presented to the upper chaser by the upper chuck. Thus in the second and each succeeding operation the lower chaser threads one end of each blank while the upper chaser threads the other end of the blank just previously threaded by the lower chaser. Upon completion of this operation when a new blank is forced into the lower chuck it will force the completed blank from the upper chuck. Thus the only operation necessary with the mechanism of the present invention is the feeding of blanks into one of the chucks and initiation of the cycle, all other parts of operation being formed automatically by the feeding mechanism. It will be noted that the provision of an automatic feeding means to feed blanks into the lower chuck would make the entire operation fully automatic.

In handling relatively short or close nipples it is necessary to provide some means to transfer the nipples from one of the chucks to the other due to the fact that their length is not great enough to span the distance between the chucks. For this purpose a transfer mechanism of the type shown in Figures 9 and 10 may be provided and the upper or second chuck may be equipped with special jaws, as shown in Figure 5. In these jaws the outer end portions of the jaws are threaded, as shown at 71, and the jaws are formed with stop shoulders 72 at the ends of the threaded portions thereof. With close nipples it is necessary to grip the nipple threads in order that there may be sufficient length of nipple projecting from the chuck for threading, and the threaded portions 71 of the jaws are threaded in the same manner as the nipples so that they can grip the nipple threads without damaging them. The stop shoulders 72 prevent the threaded ends of the nipples from extending too far into the chuck jaws and insure that the short nipples will be properly gripped by the chucks.

The transfer mechanism as shown in Figures 9 and 10 comprises a trough 73 pivoted on a horizontal pivot 74 adjacent the first or lower chuck. The trough 73 is moved between a horizontal position as shown in Figure 9 and a tilted position, as shown in Figure 10 by a control lever 75 which may be controlled by a suitable cam 15a on one of the carriages. The trough is of a size and length to receive a nipple and is positioned on the bed of the machine so that when the carriages are in their loading position it will be aligned with the chucks.

To prevent a nipple from falling out of the trough when it is tilted to the position of Figure 10 a pivoted stop arm 76 is carried by the trough and has a reduced tip 77 to project up into the trough to engage and stop a nipple therein. The opposite end of the arm 76 carries a roller 78 slidable in a slot 79 formed in a plate 81 carried by the bed of the machine. When the trough is in its upper horizontal position, as shown in Figure 9, the lever 76 will be rocked to a position in which its upper tip end is withdrawn from the trough, while when the trough is tilted downwardly, the lever will be rocked to a position to move its tip end 77 into the trough.

Nipple blanks in the trough are adapted to be moved therefrom into the second chuck by a feeding arm 82 whose lower end normally projects into the trough and which is movable horizontally parallel to the axis of the chucks. When the chucks are in the feeding position, as shown in Figure 9, the trough is elevated and the feed-

ing arm 82 is normally in the position shown in full lines. When a new blank is fed into the chuck at the left, the feeding arm will move to the dotted position and will force the nipple which was in the trough into the chuck at the right. At the same time the new blank fed into the chuck at the left will force the nipple in that chuck into the trough. As the carriage is moved forward to threading position the trough will tilt down to the position of Figure 10 so that the nipple carried thereby is below the lower end of the feeding arm 82. The tip 77 of the lever 76 will prevent the nipple in the trough from falling out, and with the trough in this position the lever 82 may be moved to the left to its starting position. When the trough is again raised to the position of Figure 9, the feeding arm will be behind the nipple in the trough in a position to force it therefrom into the second chuck.

In the threading of short nipples, instead of forcing the completed nipple completely through the second chuck the completed nipple is discharged forwardly from the chuck. As the carriage is returned from the threading position the cam member 64 will release the friction gripping jaws so that when the main chuck jaws are opened by operation of their cam control mechanism, the nipple being extremely short will fall freely from the chuck. Otherwise and except for the use of the transfer mechanism with short nipples the operation is identical on both short and long nipples and is fully automatic except for the feeding of the blanks into the first chuck.

While the mechanism of the invention has been particularly described in connection with the threading of pipe nipples, it will be apparent that many of the features of the invention are applicable to threading or other machining operations of other types. It will, therefore, be understood that the invention is not limited to the exact mechanism shown nor otherwise than by the terms of the appended claims.

What is claimed is:

1. Feeding mechanism for nipple threading machines and the like having a head rotatable on a horizontal axis comprising a carriage movable horizontally toward and away from the head, a chuck pivoted on the carriage on a vertical axis to swing from a position aligned with the head to a position at right angles thereto, movable gripping jaws in the chuck to grip a work piece, means to turn the chuck on the carriage as the carriage moves, means to move the gripping jaws to gripping position as the chuck turns, auxiliary jaws on the chuck yieldingly urged into gripping engagement with a work piece in the chuck, and means to open the auxiliary jaws during movement of the chuck in one direction.

2. Feeding mechanism for nipple threading machines and the like having a head rotatable on a horizontal axis comprising a carriage movable horizontally toward and away from the head, a chuck pivoted on the carriage on a vertical axis to swing from a position aligned with the head to a position at right angles thereto, movable gripping jaws in the chuck to grip a work piece, means to turn the chuck on the carriage as the carriage moves, means to move the gripping jaws to gripping position as the chuck turns, auxiliary jaws on the chuck yieldingly urged into gripping engagement with a work piece in the chuck, and a cam movably mounted on the carriage and engageable with the auxiliary jaws to yield when the chuck turns in one direction and to cam the

auxiliary jaws open when the chuck turns in the other direction.

3. Feeding mechanism for nipple threading machines and the like comprising a pair of carriages, means for moving the carriages simultaneously in parallel paths, a chuck pivoted on a vertical axis on each of the carriages, movable jaws in the chucks to grip work pieces, guide means simultaneously to turn the chucks in opposite directions as the carriages move from a position in which the chucks are aligned to a position in which they are parallel to each other, the chucks having openings therethrough of a size to pass a work piece whereby a work piece can pass from one chuck to the other when the chucks are aligned, and a transfer mechanism between the chucks when the chucks are aligned to receive a work piece from said one of the chucks and feed it into the other chuck.

4. Feeding mechanism for nipple threading machines and the like comprising a pair of carriages, means for moving the carriages simultaneously in parallel paths, a chuck pivoted on a vertical axis on each of the carriages, movable jaws in the chucks to grip work pieces, guide means simultaneously to turn the chucks in opposite directions as the carriages move from a position in which the chucks are aligned to a position in which they are parallel to each other, the chucks having openings therethrough of a size to pass a work piece whereby a work piece can pass from one chuck to the other when the chucks are aligned, and a transfer mechanism between the chucks when the chucks are aligned to receive a work piece from said one of the chucks and feed it into the other chuck, the transfer mechanism including a holder to receive the work piece and a movable feeding member to force the work piece from the holder into said other chuck.

5. Feeding mechanism for nipple threading machines and the like comprising a pair of carriages, means for moving the carriages simultaneously in parallel paths, a chuck pivoted on a vertical axis on each of the carriages, movable jaws in the chucks to grip work pieces, guide means simultaneously to turn the chucks in opposite directions as the carriages move from a position in which the chucks are aligned to a position in which they are parallel to each other, the chucks having openings therethrough of a size to pass a work piece whereby a work piece can pass from one chuck to the other when the chucks are aligned, and a transfer mechanism between the chucks when the chucks are aligned to receive a work piece from said one of the chucks and feed it into the other chuck, the transfer mechanism including a trough tiltable about a horizontal axis between a position horizontally aligned with the chuck jaws and a position tilted downward toward the other chuck, a stop projecting into the lower end of the trough when it is tilted downward and movable out of the trough when it is horizontal, and a feeder member movable horizontally through the trough to force a work piece therefrom into the other chuck when the trough is horizontal and to pass over a work piece in the trough when the trough is tilted.

GEORGE B. MARSDEN.
